CLAIM

I claim the ornamental design for an electrical interface, as shown and described.

DESCRIPTION

FIG. 1 is a left front bottom perspective view of an electrical interface.

FIG. 2 is a right front bottom perspective view of the electrical interface shown in FIG. 1.

FIG. 3 is a right rear bottom perspective view of the electrical interface shown in FIG. 1.

FIG. 4 is a left rear bottom perspective view of the electrical interface shown in FIG. 1.

FIG. 5 is a front view of the electrical interface shown in FIG. 1.

FIG. 6 is a bottom view of the electrical interface shown in FIG. 1.

FIG. 7 is a left front top perspective view of an electrical charger.

FIG. 8 is a left front bottom perspective view of the electrical charger shown in FIG. 7.

FIG. 9 is a right front bottom perspective view of the electrical charger shown in FIG. 7.

FIG. 10 is a right rear bottom perspective view of the electrical charger shown in FIG. 7.

FIG. 11 is a left rear bottom perspective view of the electrical charger shown in FIG. 7.

FIG. 12 is a left side view of the electrical charger shown in FIG. 7.

FIG. 13 is a right side view of the electrical charger shown in FIG. 7.

FIG. 14 is a rear view of the electrical charger shown in FIG. 7.

FIG. 15 is a front view of the electrical charger shown in FIG. 7.

FIG. 16 is a top view of the electrical charger shown in FIG. 7.

FIG. 17 is a bottom view of the electrical charger shown in FIG. 7.

FIG. 18 is a left front top perspective view of the electrical charger.

FIG. 19 is a left front bottom perspective view of the electrical charger shown in FIG. 18.

FIG. 20 is a right front bottom perspective view of the electrical charger shown in FIG. 18.

FIG. 21 is a right rear bottom perspective view of the electrical charger shown in FIG. 18.

FIG. 22 is a left rear bottom perspective view of the electrical charger shown in FIG. 18.

FIG. 23 is a left side view of the electrical charger shown in FIG. 18.

FIG. 24 is a right side view of the electrical charger shown in FIG. 18.

FIG. 25 is a rear view of the electrical charger shown in FIG. 18.

FIG. 26 is a front view of the electrical charger shown in FIG. 18.

FIG. 27 is a top view of the electrical charger shown in FIG. 18; and,

FIG. 28 is a bottom view of the electrical charger shown in FIG. 18.

The evenly spaced broken lines represent portions of the electrical interface that form no part of the claimed design. With respect to FIGS. 1-6, the claimed electrical interface is not visible in the orthogonal right side, orthogonal left side, and orthogonal top views, which are therefore omitted.
